ABSTRACT: The present invention relates to float switch apparatus having unusual stability. Broadly, the float switch apparatus of the present invention comprises a buoyant lever arm having a fulcrum at one end thereof comprising a transverse shaft. Said shaft is pivotally associated with an appropriate mount. A switch means, responsive to angular deflection, is positioned within the lever arm and the conductor wires associated with said switch are routed through the transverse shaft and exit said shaft through radial apertures provided therein. Said wires then form a helical coil about said shaft and are affixed to the mount. Additionally, for greatest efficiency and stability, it is much preferred that at least the bottom, and most preferably also the top, surfaces of the lever arm be tapered.

SHEET 1 OF 2

FIG. 1

PATENTED JUL 13 1971

3,592,981

SHEET 2 OF 2

FIG. 2

FLOAT SWITCH APPARATUS

Float switches of various types have long found service in marine and industrial applications, for example, in activating and deactivating pumps in response to changing water level. A typical prior art float switch commonly comprises a buoyant lever arm mounted on a suitable base. Associated with the lever arm is an electrical switch device which is responsive (i.e. makes or breaks contact) to angular deflection of the lever arm. The conductor wires leading from the switch device are normally routed through the lever arm in any convenient manner and, of course, eventually communicate with the electrical device desired to be operated thereby. The shapes of the lever arms utilized in prior art float switches have been subject to wide variation. Unfortunately, however, the float switches of the prior art have most frequently not achieved the full measure of their potential in marine applications, due, in large measure, to a general lack of stability and/or responsiveness under the marine environment. Specifically, prior art switches have tended to be excessively responsive to merely transient changes in liquid levels such as often occur in the bilges of a pitching or rolling vessel. In consequence, electrical apparatus operated under such conditions and utilizing prior art float switches have often been subjected to excessive wear and tear due to an unnecessarily excessive number of start-stop cycles.

In accordance with the present invention, however, the aforementioned stability difficulties have been greatly reduced.

It is a principal object of the present invention to provide a novel float switch device having unusually stable operating characteristics.

It is another object of the present invention to provide a novel float switch which have an unusually long operating life and which is constructed so as to prevent electrical arcing.

It is another object of the present invention to provide a novel float switch wherein the switch mechanism is contained within the lever arm for maximum compactness.

Other objects and advantages of the present invention will in part be obvious and will in part appear hereinafter.

A better understanding of the apparatus of the invention can be had by reference to the drawings forming part hereof wherein:

FIG. 1 is a partially sectionalized isometric schematic view of the float switch apparatus of the instant invention.

FIG. 2 comprises a schematic side elevation of the apparatus of FIG. 1 in two representative stages of operation.

Referring now to the drawings, buoyant lever arm 1 has a fulcrum at one end thereof as represented by shaft means 3 extending laterally from both sides thereof. Said shaft 3 is in fixed relationship with lever 1 and is received in rotational relationship by apertures 4 of mount means 5 thereby establishing pivotal relationship of said lever arm relative to said mount means. The electrical components of the float switch comprise a switch device 7 responsive to angular deflection, and wire conductors 9 in electrical communication with said switch device. Said switch device 7 can be conveniently mounted within the lever arm by means of a suitable bedding compound 11.

While any electrical switch responsive to angular displacement is suitable, I much prefer for the sake of simplicity, reliability, nonarcing characteristics, and efficiency, those switch devices characterized by an insulative capsule 6 which contains a globule of a liquid electrolyte therein and which has at one end thereof contact leads. In operation, referring now specifically to FIG. 2, liquid electrolyte globule 8 remains out of contact with said leads (Stage A) until an upward angular deflection of the capsule is effected such as achieved when lever arm 1 is displaced upwardly by rising liquid levels to the position illustrated as Stage B. When such angular deflection occurs, the electrolyte globule bridges contacts 10 and thus completes the circuit. At present, the most common of electrolytes encountered in such switches is mercury; thus, for the

purposes of the present specification the general term, "mercury switch," encompasses the preferred switch device. Needless to say, however, any electrolyte or conductive material such as small metal balls or metal powder can be utilized although liquid electrolytes, and especially mercury, are preferred.

A critical feature of the invention resides in the manner by which conductor wires 9 which communicate with said switch device are routed from the lever arm. In accordance with the present invention, the routing is achieved in a manner which allows the level arm to move upwardly and downwardly with a minimum of interference or drag. Specifically, in accordance with the present invention, said wires are routed through shaft 3 and are exited therefrom through radial apertures 13. The wires are then wound about their respective shafts for at least one-half turn and most preferably at least one whole turn so as to form coils 19 and 20, preferably in such a direction that any resistance to motion of the lever arm will occur when the float is rising and so that assistance to motion of the lever arm is provided in the downwardly direction. The so coiled conductor wires are then firmly affixed to mount 5 by any suitable means. The anchoring or fixing of the conductor wires can be achieved in any suitable manner such as by routing said wires through holes 15 provided in floor 17 of mount 5 and knotting each of the wires at the exit sides of their respective holes; or alternatively, knotting the conductor wires together below floor 17. Still another method for anchoring which I have found particularly advantageous comprises applying a suitable cement at holes 15. With respect to said sealing function, it should be noted that it is most important in accordance with the present invention that lever arm 1 be leakproof. In the particular apparatus shown in FIGS. 1 and 2, the only pathways available for leakage into said arm are through apertures 13, and ends 21 and 23 of shaft 3. Obviously, said potential leakage pathways should be blocked, for instance by plugging of said apertures with a suitable sealant.

In any case, optimum adjustment of the length of the conductor wire coils 19 can generally be determined during assembly of the apparatus by maintaining lever arm 1 in its upwardmost intended operating positions and taking up on each of the conductor wires sufficiently to leave just a little slack in coils 19 and 20. The conductor wires may then be anchored to the mount means thereby achieving sufficient coil diameter to allow free deflection of lever arm 1 thereby providing excellent responsiveness and reliability to the present switch. The precise reasons why the coils result in superior operational stability are not fully understood. However, it is believed that the fact that a wire coil exhibits much less resistance to an increase in diameter than to direct bending is an important factor. Another advantage achieved by use of the above-described coils resides in the equalization of operating tensions on the conductor wires themselves, thereby obviating to a large extent premature crystallization and/or fracture of said wires at single points of stress concentration. While single strand or solid wires may be utilized with substantial benefits, it is nevertheless generally preferred to employ conductor wires comprising at least about three strands, thereby even further alleviating the possibility of undesirable stress concentrations occurring within the conductors during operations.

Another important feature of the apparatus of the present invention which results in even further stability benefits, resides in the particular shape of lower and upper surfaces 30 and 32 respectively of lever arm 1. Specifically, it has been found that bottom surface 30 should be tapered toward end 36 and shaped so that surface 31 of capsule 6 and surface 30 are parallel. Thus a rectangular lever arm 1 would not be very efficient as relates to buoyancy, and moreover, a rectangular arm 70 would have to be mounted higher in order to allow arm 1 to swing through any given arc. The net result therefore of utilizing a rectangular arm would be a switch which would require a deeper ambient water level for activation and which would leave more water at shut off. When, however, bottom surface 30 is tapered, it then becomes most desirable for top surface

32 to be tapered also in order to maintain a proper weight relationship for lever arm 1. The extent of tapering is not critical but tapering at angles between 5 and 25 has been found to be effective.

Another very important factor in the present invention is the shape of capsule 6 comprising switch 7. Said capsule preferably has an angle therein of between 15° and 75°, about 25° having been found to be excellent. The angle is most important in order that the switch open and close at substantially different liquid levels. Thus the shifting of the electrolyte from one end to the other in an angled capsule affects the "time delay" response and therefore the stability of the present switch. It is important therefore in accordance with the present invention that the electrolyte or conductive material move from substantially one extremity of capsule 6 to the other, shifting dramatically the location of the center of gravity and assuring extended time delay coupled with small size and low cost.

Still another feature which results in greater sensitivity and stability during operations of the present switch resides in the presence of hairline ridges 22 about the ends of shaft 3. It is believed that these ridges serve to minimize the contact area between the shaft ends and the interior surfaces of mount walls 25 thereby effectively reducing the frictional forces that are developed. Also, apertures 4 should have a circular cross-sectional shape in order to provide only slight contact and reduce frictional drag.

Still another feature of the present float switch apparatus resides in the positioning on mount 5 and/or on lever arm 1 of stop means which prevent lever arm 1 from rising to the vertical position. In FIG. 1, small projections 40 on the surface of 30 mount 5 and arm 1 which are positioned so as to collide with one another when arm 1 describes an angle of about 75° from the horizontal serve as the stop means.

Materials of construction which are suitable for the nonelectrical components of the float switch apparatus of the present invention are obviously subject to wide variation. Various metals such as copper, brass, steel, etc., are, of course, suitable. However, the structural members of float switches in general are normally well-suited to production by thermoplastic molding techniques. Thus, for purposes of construction ease and in order to readily provide a generally inert character, polymeric resins such as polyethylenes, polyamides, polystyrenes, polycarbonates, and the like, are much preferred. In particular, polymeric resins of the polyacetal type $(-\text{OCH}_2-)_n$ have been found to be exceptionally useful

45

materials of construction. It should be remembered that lever arm 1 must be as light as possible in order to float readily (have a high ratio of buoyancy to weight) and yet heavy enough to be sure of rotating downwardly against frictional resistance and the tendency to remain up because of sludge or thick grease accumulations.

Obviously, many changes can be made in the above description and the specific disclosures in the drawings without departing from the scope and intent of the invention. For instance, while the float switch apparatus specifically described herein operates in such a manner as to make contact upon an upward angular deflection of the lever arm, clearly the making of contact can also be effected upon downward deflection thereof such as by altering the position of switch device 7 by 15 180°.

What I claim is:

1. A novel float switch comprising a buoyant lever arm having a fulcrum at one end thereof comprising a transverse shaft pivotally associated with a mount, said lever arm the bottom

20 surface of which tapered toward the free end thereof containing therein and in fixed relationship with respect thereto a switch means responsive to angular deflection said switch means comprising an airtight capsule having an angle in at least the bottom wall thereof of between about 15° and about 75°, and containing a small amount of an electrolyte and contact wires located at one end thereof, said contact wires being connected to leads which exit said lever arm through radial openings in said transverse shaft and then loop around said transverse shaft at least one-half turn.

2. The switch of claim 1 wherein the bottom surface of the capsule at the end where the contact wires are located is parallel to the tapered bottom surface of said lever arm.

3. The switch of claim 1 wherein the top surface of said arm is also tapered toward the free end thereof.

4. The float switch of claim 1 wherein said contact wires after looping around said shaft at least one-half turn pass through said mount and are secured.

5. The float switch of claim 1 wherein said transverse shaft and said mount are in contact only through hairline ridges.

6. The float switch of claim 1 wherein the electrolyte comprises mercury.

7. The float switch of claim 1 wherein stop means are provided which prevent said lever arm from rising to the vertical position.
